UNITED STATES PATENT OFFICE

ERNEST C. STYBERG, OF RACINE, WISCONSIN, ASSIGNOR TO THE STOVER SIGNAL ENGINEERING COMPANY, OF MILWAUKEE, WISCONSIN, A CORPORATION OF WISCONSIN

DESIGN FOR A CASING FOR AN ICE-CREAM FREEZER

Application filed June 8, 1929. Serial No. 31,600. Term of patent 14 years

To all whom it may concern:

Be it known that I, ERNEST C. STYBERG, a citizen of the United States, residing at 1600 Winslow Avenue, Racine, in the county of Racine and State of Wisconsin, have invented a new, original, and ornamental Design for a Casing for an Ice-Cream Freezer, of which the following is a specification, reference being had to the accompanying drawing, forming a part thereof.

The figure is a perspective view of a casing for an ice-cream freezer, showing my new design.

I claim:

The ornamental design for a casing for an ice cream freezer as shown.

In witness whereof, I hereunto subscribe my name this 4th day of June, 1929.

ERNEST C. STYBERG.
